UNITED STATES PATENT OFFICE.

ARCHIBALD EATON GOLDSPIK, OF LONDON, ENGLAND.

PLAYER PIANO.

1,402,595.

Specification of Letters Patent.

Patented Jan. 3, 1922.

Application filed October 6, 1920. Serial No. 415,105.

To all whom it may concern:

Be it known that I, ARCHIBALD EATON GOLDSPIK, a subject of the King of England, residing at London, in England, have 5 invented certain new and useful Improvements in Player Pianos, of which the following is a specification.

This invention is for improvements in or relating to player-pianos of the type where- 10 in (1) the general intensity of playing is controlled for bass and treble by a choker valve in a conduit leading from the exhaust apparatus to a striker pneumatic trunk, (2) the accenting of particular notes or chords 15 is controlled by a secondary pneumatic valve in the same or another similar conduit, and (3) the control of the motor comprises valves for general control of tempo (called tempo valve), for voluntary control 20 of tempo (called retard valve), for re-winding and for closing all communication from the vacuum-effect apparatus to the striker-pneumatic trunk during re-winding.

Heretofore it has been customary to 25 mount a vacuum chest with the intensity and accenting controls below the keyboard in the main channel leading directly from the vacuum reservoir upwards to the striker-pneumatic trunks. A serious drawback of 30 this arrangement was that the intensity and accenting controls were relatively difficult of access for inspection and repairs. The motor control has heretofore sometimes been mounted below the keyboard and associated with the intensity and accenting controls; alternatively, it has been arranged 35 above the keyboard in a vacuum chest which was separated from that provided for the intensity and accenting controls.

40 An important object of this invention is to reduce the number of secondary pneumatic valves required in the accenting control for the bass and treble.

45 Another object is to obviate the above-mentioned drawback and to provide a construction of control apparatus such that all of the control valves shall be more readily accessible than heretofore.

50 A further object is to provide a unitary construction of control box or vacuum chest, on or in which are accommodated the intensity and accenting control valves for the bass and treble, and also the motor-control valves.

55 According to this invention, therefore,

there is provided in a player-piano of the type described an accenting control comprising (a) one secondary pneumatic valve arranged to close a conduit connecting between the vacuum-effect apparatus and the 60 striker-pneumatic trunk, and (b) two primary pneumatic valves each operatively connected with and controlling the secondary pneumatic, one being controllable from the tracker-bar, and the other usually energized 65 by opening its pneumatic port to atmosphere so as to close said secondary pneumatic valve.

Conveniently, an accenting control as just described above is combined with a vacuum 70 chest connected between the vacuum-effect apparatus and the striker-pneumatic trunk, and one of the two primary pneumatics has its port normally closed to atmosphere and is energized by connection to atmosphere 75 through an accenting conduit from the tracker-bar, and the second of the two primary pneumatics is energized by manually opening its port to atmosphere so as to close said secondary pneumatic valve. 80

According to another feature of the invention, for the purpose of rapidly changing over from automatic to manual control of the accentuation, two conduits are controlled at one end by the two aforesaid primary valves, a third conduit is connected at one end with the aforesaid secondary valve, and means, for example a manually-operated slide-valve, is provided to place the other end of the said third conduit into 85 open communication at will with either of the other ends of the two first-named conduits.

According to a further feature of the invention a single control box is disposed 95 above the keyboard and comprises a vacuum chest having in or on it the usual governing devices and pneumatics which control (a) the motor, (b) the intensity, (c) the accenting and (d) the re-winding. 100

Other features of the invention will be described hereinafter and pointed out in the claims.

The invention is diagrammatically illustrated by way of example in the accompanying drawings, wherein:

Figure 1 is an end elevation, partly in section on the line I—I in Figure 2 and partly broken away, showing one form of player-piano embodying the improvements accord- 110

ing to the invention, various parts of the piano that are not necessary for the understanding of the invention being omitted;

Figure 2 is a front elevation of the player-piano shown in Figure 1, parts thereof having been removed and others being shown broken away; in this figure the treble and base ends of a control box for accommodating the various accenting valves in a unitary structure with the motor-control valves is shown with its front cover in position, while the middle portion of the box is shown with its front cover removed to expose the motor-control valves;

Figure 3 is an enlarged longitudinal sectional elevation of the treble end of the control box and the valves therein;

Figure 4 is a partial detail vertical sectional elevation taken on the line IV-IV in Figure 2, and

Figure 5 shows an alternative arrangement of the treble intensity control valve with its bellows mounted outside the control box.

Like reference letters designate like parts throughout the several views.

Referring to the drawing, the player-piano having a keyboard 1, is provided as usual with vacuum-effect apparatus comprising feeders or pumps 2, and vacuum reservoirs 3 below the keyboard; above the keyboard is the usual striking action, designated generally by the numeral 4, together with a tracker-bar 5, striker pneumatics 6, and striker-pneumatic trunks 7.

A single control box designated generally by the numeral 8 and constituting a vacuum chest for accommodating not only bass and treble intensity and accenting controls, but also the motor control, is arranged above the keyboard 1 in front of the striking action 4.

This vacuum chest 8, which extends from end to end of the piano and is mounted on main wind trunks 9 in the manner described hereinafter, comprises a base board 10, a top board 11, and a middle board or partition 12, which divides the chest into an upper chamber 13 and a lower chamber 14. The two ends of the vacuum chest 8 are partially but not completely divided off from the middle portion thereof by two vertical partition walls 15, 16 to constitute treble and bass valve-chambers designated generally by the numerals 17, 18 respectively. These two chambers and the valves associated therewith are similar to one another, so that a description of the treble valve-chamber 17 (Figure 3) will suffice for the two.

Three ports 19, 20, 21, are provided in the partition 12 in the chamber 17, into the lower part of which opens at its end a main suction channel 22 leading to a vacuum reservoir 3. The connection be-

tween the vacuum-effect apparatus and the wind trunks is by way of one or both of the ports 19 and 20 and the port 21. This port 21 is connected to the striker-pneumatic trunks 7 by a conduit 23 which crosses but does not close the lower part of the valve-chamber 17 at 24, then continues in the base board 10 and opens downwardly into the main wind trunk 9, in the manner described hereinafter. 75

The port 19 is controlled by an intensity choker valve 25 that is mounted in the upper part 13 of the chamber 17. The port 20 is normally closed by a secondary accenting valve 26 mounted in the lower part 14 of the valve-chamber 17, and the port 21 is controlled by a rewind cut-off valve 27 referred to more particularly hereinafter. It will be seen that when these three valves 25, 26 and 27 are in the position shown 80 in Figure 3, suction is supplied to the striker-pneumatic trunks 7 by way of the valve 25 which thus regulates the general intensity of playing, whilst when the valve 26 is opened in the manner described hereinafter, the full force of the suction is applied to the wind trunks 7 by way of the lower part 14 of the chamber 17 the port 20 and the passage 24, 23 which thus constitutes a main accenting conduit. 90

The accenting device comprises the above mentioned secondary pneumatic valve 26 and two primary pneumatic valves 28 and 29 associated therewith. The one primary valve 29, which may be called the accenting primary valve, is arranged to be energized from the tracker bar to open the secondary valve 26 when it is closed, and the other primary valve 28 which may be called the accenting cut-off primary valve, is arranged to be operated manually to close the secondary valve 26 when it is open. A third primary pneumatic valve 30, which may be called the re-wind cut-off primary valve, is arranged to operate the re-wind cut-off valve 105 27 which is thus a secondary valve and is referred to in greater detail hereinafter. 110

Two sets of three primary valves 28, 29, 30 are provided respectively at the treble and bass ends of the middle portion of the 115 vacuum chest, and the ports controlled by these valves, hereinafter referred to as the outlet ports, are situated in a part of the partition 12 which constitutes the bottom of a box-like chamber 31 open to the atmosphere. This chamber 31 is formed at each end of the valve chest by the wall 15 or 16 and a wall 32 of the same size and parallel therewith in the chamber 13. The top of the chamber 31 is provided with holes, whereof one is shown at 79, which enable a screwdriver to be inserted for unscrewing the upper seating plate of the valve 29. These holes may be covered with metal gauze 80 for keeping dust out of the air-chamber 31. 130

The pneumatic port 33 of each valve 29 is connected by an accenting conduit 34 with the tracker-bar 5, and the pneumatic port 35 of each primary valve 28 is connected by a conduit 36 with a control lever 37, whereof one is provided for the bass and one for the treble. The two outlet ports 38 and 39, respectively, of the primary valves 29 and 28 are respectively connected by conduits 40 and 41 with two ports 42 and 43 in the body 44 of a slide-valve, whereof the valve proper 46 has a port 47 connected by a flexible conduit 48 to the pneumatic port 49 of its allotted secondary accenting valve 26. The two slide-valves 46, one at the bass and the other at the treble, are connected together by a tie-rod 50 having an operating handle 51, so that they can be operated together in unison to bring the bass and treble tracker-bar accenting controls into and out of operation simultaneously.

Assuming that it is desired to automatically accentuate the notes or chords that are being played, the handle 51 will be moved to place the slide-valves 46 in the position shown in Figure 2, in which the outlet ports 38 are in open connection with the pneumatic ports 49. As soon as a hole in the paper registers with the accenting hole in the tracker-bar connected to one of the accenting conduits 34, the allotted primary valve 29 will be energized, the port 38 is thereby closed to atmosphere in the box 31 and opened to suction in the chamber 14, so that suction is supplied by way of the conduit 40 and the slide-valve 46 to the pneumatic port 49 of the accenting valve 26, whereby the port 20 is opened, so that the full force of the suction is admitted to the wind trunks 9 and 7. When atmosphere is cut off by the music sheet from the port 33, the valve 26 is de-energized and is closed owing to the primary valve 29 closing its outlet port 38 to suction and opening it to atmosphere. When it is desired to cut off the accentuation from the tracker bar, the handle 51 is operated to shift the slide-valves 46 so that the ports 47 register with the ports 43, whereupon the secondary accenting valves 26 are held open by suction supplied by way of the outlet ports 39 of the primary cut-off valves 28. In this position of the accenting device, atmosphere can be admitted manually at will to either of the pneumatic ports 35 of these primaries by the control levers 37. When an accenting cut-off primary valve 28 is thus energized its outlet port 39 is opened to atmosphere in the chamber 31, whereupon atmosphere is supplied by way of one of the ducts 41, the slide-valve 46 and the conduit 48 to the pneumatic port 49 of the allotted secondary accenting valve 26 to close the same, thereby shutting off the main force of the suction from the wind trunks 9 and 7.

It will be seen that the accenting control as described above comprises only two secondary accenting valves, one for the treble and one for the bass, which are controlled each by two primaries. The number 70 of secondary valves employed is thus reduced to a minimum, so that the described arrangement has the advantage of simplicity and reduction of cost of manufacture. Further, the liability of repairs being required is reduced to a minimum.

As mentioned above, the motor control is also accommodated in the described control-box or vacuum chest. This control may comprise, as usual, an anti-fluctuation or 80 choker valve, a tempo slide-valve, a retard valve and a re-winding valve. In the present construction, a choker valve 52 is provided near the bass end of the middle portion of the vacuum chest and is arranged to 85 control a port 53 in the partition 12 connecting the upper and lower parts 13, 14 of the chest. A tempo slide-valve 54 is provided in the upper part of the chest near the middle thereof, and near the same in 90 the lower part of the chest is a re-winding valve 55 that controls a port 56 in the partition 12. A retard valve 57 is arranged adjacent the wall 32 at the treble end of the valve chest and controls a port 58 that leads 95 to the motor.

When re-winding is to occur, the re-winding valve 55 is opened to admit the full force of the suction by way of the port 58 to the motor, and at the same time the re-winding cut-off valves 27 (Figure 3) are closed to cut off the suction from the wind trunks. For this purpose the re-winding control mechanism comprises a rocking valve designated generally by the numeral 105 59. Two conduits 60 and 61 opening respectively at one end into the pneumatic ports 62 of the bass and treble primary valves 30 open at their other ends into two ports 63 and 64 respectively, in the body portion 65 of the valve 59. A conduit 66 opens at one end into the pneumatic port 67 of the re-winding valve 55 and at its other end into a port 68 situated between the two ports 63 and 64. The rocking member 69 of the valve 110 59 when operated by its handle 70 admits atmosphere to the three conduits 60, 61 and 66, simultaneously, and thereby energizes the two primary valves 30 and the re-winding valve 55. The outlet port 71 of each primary valve 30 is connected by a conduit 72 with the pneumatic port 73 of its allotted secondary valve 27, so that the two re-winding cut-off valves 27 are energized at the same time as the re-winding valve 55 is 120 opened and immediately close the ports 21, and thereby cut off the suction from the wind trunks.

It will be seen from the above that the intensity and accenting control valves for 130

the bass and treble and also the motor control valves are accommodated in the described control box and form therewith a single unitary structure. The front of the control box is normally closed by a front wall divided into three parts screwed into position, whereof parts of two are shown at 74 in Figures 1 and 2. When this cover is removed the various valves are situated in 10 such a position that they can be readily inspected, and repaired if necessary, by a person seated on the usual piano-stool in front of the instrument.

The intensity valve 25 shown in Figure 3 15 has its pneumatic 75 situated inside the valve-chamber 17, and controlled by a spring 76 that is mounted outside the control box and tends to hold the valve 25 open against the action of the suction. If desired, however, the pneumatic 75 can be 20 situated outside the control box as shown in Figure 5. In this case the suction, instead of acting on the outside of the pneumatic as in the arrangement shown in Figure 3, 25 acts by way of a port 77 on the inside of the same, and the pneumatic is connected to the closure member of the valve by a rod 78.

The control-box is secured in position by means of two wooden blocks 81 (Figure 1) 30 fixed one at each end to its bottom and held against the rear faces of the main wind trunks 9 by bolts 82. Each of these blocks 81 has in it an L-shaped duct, whereof the upper end registers with the adjacent end 35 of the allotted accenting conduit 23, and the lower end registers with the adjacent end of the passage in the trunk 9. This arrangement enables the control box to be readily placed in and removed from its normal position.

It will be appreciated that various modifications may be made in the above-described apparatus without departing from the scope of the invention as defined in the claims.

What I claim as my invention and desire to secure by Letters Patent is:—

1. In an automatic key instrument, the combination with a tracker, a main wind chest, and means for exhausting air from the latter, of a single control box which is located above the keyboard and comprises a control wind chest, means connecting the control wind chest with the main wind chest, a striker pneumatic trunk connected by way 50 of the control box with the main wind chest, motor control means, intensity control means and rewinding control means provided in said control box, and an accenting control comprising primary and secondary pneumatic valves mounted in said control box and arranged to control the connection of said trunk with the main wind chest.

2. In an automatic key instrument, the 60 combination with a tracker, a main wind

chest and means for exhausting air from the latter, of a single control box which is located above the keyboard and comprises a control wind chest, means connecting the control wind chest with the main wind 70 chest, a striker pneumatic trunk connected by way of the control box with the main wind chest, motor control means, accenting control means and rewinding control means provided in said control box, and an intensity control comprising a secondary pneumatic valve mounted in said control box and arranged to control the connection of said trunk with the main wind chest, and two primary pneumatic valves 80 mounted in said control box and arranged each to control said secondary pneumatic valve independently and alternatively of the other.

3. In an automatic key instrument, the 85 combination with a tracker, a main wind chest and means for exhausting air from the latter, of a single control box which is located above the keyboard and comprises a control wind chest, means connecting the control wind chest with the main wind chest, a striker pneumatic trunk connected by way of the control box with the main wind chest, motor control means, intensity control means and rewinding control means 90 provided in said control box, and an accenting control comprising a secondary pneumatic valve mounted in said control box and arranged to control the connection of said trunk with the main wind chest, and two primary pneumatic valves mounted in 95 said control box and arranged each to control said secondary pneumatic valve independently and alternatively of the other; one of said primary pneumatic valves being 100 controllable from the tracker, and means for manually energizing the pneumatic of the other so as to close said secondary pneumatic valve to act as an intensity control.

4. In an automatic key instrument, the 110 combination with a tracker, a main wind chest and means for exhausting air from the latter, of a single control box which is located above the keyboard and comprises a control wind chest, means connecting the control wind chest with the main wind chest, a striker pneumatic trunk connected by way of the control box with the main wind chest, motor control means, intensity control means and rewinding control means 115 provided in said control box, and an accenting control comprising a secondary pneumatic valve mounted in said control box and arranged to control the connection of said trunk with the main wind chest, a conduit 120 connected to the pneumatic of said secondary valve, two primary pneumatic valves mounted in said control box, two conduits controlled by said primary valves, means for connecting the two latter conduits al- 125 130

ternatively with the first conduit, means for connecting the pneumatic of one of said primary valves with the tracker, and means for manually energizing the pneumatic of 5 the other primary valve.

5. In an automatic key instrument, the combination with a tracker, a main wind chest, and means for exhausting air from the latter, of a single control box which is 10 located above the keyboard and comprises a control wind chest, means connecting the control wind chest with the main wind chest, a striker pneumatic trunk connected by way of the control box with the main 15 wind chest, motor control means, intensity control means and rewinding control means provided in said control box, and an accenting control comprising a secondary pneumatic valve mounted in said control 20 box and arranged to control the connection of said trunk with the main wind chest, a conduit connected to the pneumatic of said secondary valve, two primary pneumatic valves mounted in said control box, two conduits 25 controlled by said primary valves, a manually operable slide valve arranged to connect the two latter conduits alternatively with the first conduit, means connecting the pneumatic of one of said primary valves 30 with the tracker, and means for manually energizing the pneumatic of the other primary valve.

6. In an automatic key instrument, the combination with a tracker, a main wind 35 chest and means for exhausting air from the latter, of a single control box which is located above the keyboard and comprises a control wind chest, means connecting the control wind chest with the main wind chest, 40 a striker pneumatic trunk connected by way of the control box with the main wind chest, motor control means, intensity control means and rewinding control means provided in said control box, and an accenting control 45 comprising a secondary pneumatic valve mounted in said control box and arranged to control the connection of said trunk with the main wind chest, and two primary pneumatic valves mounted in said control box 50 and arranged each to control said secondary pneumatic valve independently and alternatively of the other, one of said primary pneumatic valves being controllable from the tracker, and means for manually energizing the pneumatic of the other so as to 55 close said secondary pneumatic valve to act as an intensity control, the valve port of the primary valve controlled from the tracker normally opening to atmosphere and when 60 its pneumatic is energized opening to wind so as to open said secondary valve, and the valve port of the second primary valve normally opening to wind, and, when its pneumatic is energized, opening to atmosphere so 65 as to close said secondary valve.

7. In an automatic key instrument, the combination with a tracker, a main wind chest, and means for exhausting air from the latter, of a single control box which is located above the keyboard and comprises a 70 control wind chest and a valve chamber that opens into the latter and has three ports, means connecting the main wind chest with two of said ports, an adjustable valve arranged to control one of these two ports, a 75 striker pneumatic trunk, means connecting the latter with the third of said ports, a rewind cut-off valve arranged to close said third port, and an accenting control comprising a secondary pneumatic valve arranged to control the other of said two ports, and two primary pneumatic valves mounted in said control box and arranged each to control said secondary valve independently and alternatively of the other. 80

8. In an automatic key instrument, the combination with a tracker, a main wind chest, and means for exhausting air from the latter, of a single control box which is located above the keyboard, has an inlet 90 in its bottom and comprises a control wind chest, means connecting the control wind chest with the main wind chest, a striker pneumatic trunk, a block mounted on the bottom of the control box and detachably 95 secured to said wind trunk, which block has a passage that opens at one end into said inlet and at its other end into the wind trunk, motor control means, intensity control means and rewinding control means 100 provided in said control box, and an accenting control comprising primary and secondary pneumatic valves mounted in said control box and arranged to control the connection of said trunk with the main wind 105 chest.

9. In an automatic key instrument, the combination with a tracker, a main wind chest, and means for exhausting air from the latter, of a single control box which is 110 located above the keyboard and comprises a control wind chest and a valve chamber that opens into the latter and has three ports, means connecting the main wind chest with two of said ports, an adjustable valve 115 arranged to control one of these ports, a bellows situated in said valve chamber and connected with said valve, said bellows opening to atmosphere through a port in the wall of the valve chamber, a striker 120 pneumatic trunk, means connecting the latter with the third of said ports, a rewind cut-off valve arranged to close said third port, and an accenting control comprising a secondary pneumatic valve arranged to control the other of said two ports, and two primary pneumatic valves mounted in said control ports and arranged each to control said secondary valve independently and alternatively of the other. 125

10. The combination with a tracker, a main wind chest, and means for exhausting air from the latter, of a vacuum chest comprising an accenting conduit, means connecting one end of said conduit with the main wind chest, a striker pneumatic trunk connected with the other end of said conduit, a secondary pneumatic accenting valve arranged to control said accenting conduit, and two primary pneumatic valves situated in said vacuum chest and arranged each to control said secondary valve independently and alternatively of the other, one of which primary pneumatics is controllable from the tracker, and the other is controllable manually.

11. The combination with a tracker, a main wind chest, and means for exhausting

air from the latter, of a vacuum chest comprising an accenting conduit, means connecting one end of said conduit with the main wind chest, a striker pneumatic trunk connected with the other end of said conduit, a secondary pneumatic accenting valve arranged to control said accenting conduit, and two primary pneumatic valves situated in said vacuum chest, means for operatively connecting either of said primary pneumatic valves independently of the other with said secondary valve, one of which primary pneumatics is controllable from the tracker, and the other is controllable manually.

In testimony whereof I affix my signature.

ARCHIBALD EATON GOLDSPIK.
